[57] CLAIM

The ornamental design for a dispensing closure, as shown.

DESCRIPTION

FIG. 1 is a top perspective view of a dispensing closure showing our new design with the dispensing spout being opened and the spout closure being free;

FIG. 2 is a top plan view thereof showing the spout closure affixed to the spout;

FIG. 3 is a top plan view thereof showing the spout closure affixed to the staging post; and

FIG. 4 is a cross sectional view of FIG. 3 taken along line 4—4.

FIG. 1

FIG. 2

FIG. 3

FIG. 4
